(57) **CLAIM**

I claim the ornamental design for a nail polish mixing tool, as shown and described.

DESCRIPTION

FIG. 1 is a front perspective view of the nail polish mixing tool of the present invention;

FIG. 2 is a front elevational view of the nail polish mixing tool of the present invention;

FIG. 3 is a rear elevational view of the nail polish mixing tool of the present invention;

FIG. 4 is a left hand side elevational view of the nail polish mixing tool of the present invention;

FIG. 5 is a right hand side elevational view of the nail polish mixing tool of the present invention;

FIG. 6 is a top view of the nail polish mixing tool of the present invention; and,

FIG. 7 is a bottom view of the nail polish mixing tool of the present invention.

1 Claim, 4 Drawing Sheets
